PORTABLE DISPENSER UNIT

Harry J. McDargh, Jr., Atlanta, Ga.

Application April 7, 1944, Serial No. 529,936

2 Claims. (Cl. 222—126)

1

The object of my invention is to provide a cheap, readily assembled, merchantable package for powdered materials, such as tooth powder, from which the contents may be readily extracted in appropriately measured quantities without waste and in such form as to be readily picked up by a tooth brush.

The accompanying drawing illustrates my invention.

Fig. 1 is a perspective view of the several parts of my improved package preliminary to assembly;

Fig. 2 is a fragmentary cross-section of the delivery end of a completed and filled package with the parts in normal non-delivery position;

Fig. 3 is a view similar to Fig. 2 with the parts in delivery position;

Fig. 4 is a diagram showing the initial handling position preliminary to presentation of a measured quantity of the contents of the package; and

Fig. 5 is a view similar to Fig. 4 with the parts in position for extraction of a measured quantity of the contents.

In the drawing 10 indicates the main body of my package which may preferably be formed of a single sheet of material bent or moulded to the illustrated shape and provided, adjacent its base, with a discharge opening 11. The opposite sides of the U formed by the sheet 10 are closed by plates 13, 13, each provided at its lower end with a circular opening 14. Journalled in the openings 14 are cylindrical trunnions 15, 15, forming parts of a cylindrical barrel 16 provided with an axially extending measuring pocket 17 and also provided with a radially projecting stop finger 18. Arranged within the bight of sheet 10 between the end walls 13, 13 is a rectangular funnel 19 having inclined end and side walls so proportioned at its largest width and length as to contact the opposed sides of sheet 10 and the end walls 13 and with its end walls notched at their lower edges, as indicated at 20, to contact and fit the periphery of barrel 16.

The upper end of the package is closed by the top plate 22 which covers the opening formed by the upper ends of sheet 10 and end plates 13.

The parts may be made of any suitable light weight material, such as a relatively stiff pulp board, sheet metal, or preferably, one of the cheaper plastics.

Barrel 16 having been placed in the bight of sheet 10, end plates 13 and funnel 19 are then positioned, and parts 10, 13 and 19 suitably secured together. The space between the upper ends of sheet 10 and end walls 13 is then filled with the tooth powder and top plate 22 is fixed

2

in position, whereupon the package is ready for merchandising, the pocket 17 of barrel 16 being aligned with the lower end of funnel 19 and sufficiently held against accidental rotation of barrel 16 by the friction between the parts.

The ends of the trunnions 15 are so located that, in use, the user may grasp the main body of the package in one hand and engage the exposed ends of the trunnions 15 with the thumb and a finger of the other hand, as indicated in Fig. 4, thereupon swinging one hand relative to the other so as to rotate barrel 16 to bring pocket 17, with its contents, to an exposed position opposite opening 11, as indicated in Figs. 3 and 5.

The package may then be held in one hand while the brush 25 may be engaged by the hand which previously engaged trunnions 15 and used to extract the exposed powder from pocket 17. Preferably, the exposed ends of trunnions 15 will lie flush with, or slightly projected beyond, the outer surfaces of the walls 13, 13.

As is clearly shown in Figs. 2 and 3, the stop pin 18 will engage the base of the body 10 in one extreme of relative movement of the parts, and 25 will engage a side wall of the funnel 19 in the opposite extreme thereof.

I consider it quite desirable that the opening 11 be located in the front or rear wall of the body 10, and that the width of said opening be considerably less than ninety degrees of the arc of barrel 16, and substantially equal to the peripheral width of the mouth of the pocket 17 which, in turn, should be greater than the width of the mouth of the funnel 19.

By this arrangement, the user will have the main body of the package in substantially horizontal position at the time of extraction of material from pocket 17 and if he is careless and refrains from reversely rotating barrel 16 to the position shown, in Fig. 2, any material remaining in the pocket will lie therein without spilling.

I claim as my invention:

1. A dispensing package comprising a main hollow body, comprising opposite side walls, a front wall, a rear wall, and opposite end walls, a transverse opening in said front wall near one end wall, aligned ports in said side walls near said one end wall, a measuring barrel having trunnions projecting from its opposite ends and formed with a radially opening pocket, said trunnions being journal mounted in said ports and projecting therethrough, and said pocket, in one position of said barrel relative to said main body, registering with said transverse opening and in another relative position communicating with the

interior of said main body, said trunnions being formed with broad free ends engageable, respectively, by the thumb and finger of one hand of an operator to hold said barrel against rotary movement while, with his other hand, the operator grasps said main body and turns the same about the axis of said barrel to vary the relative positions of said barrel and said main body whereby to shift said transverse opening and said pocket selectively into and out of registry.

2. A dispensing package comprising a main hollow body, comprising opposite side walls, a front wall, a rear wall, and opposite end walls, a transverse opening in said front wall near one end wall, aligned ports in said side walls near said one end wall, a measuring barrel having tunnions projecting from its opposite ends and formed with a radially opening pocket, said trunnions being journal mounted in said ports and projecting therethrough, a funnel within said

main body having its large end in communication with the interior of said body and facing the other end wall and having its small end contoured to correspond to said measuring pocket and located substantially in contact with the periphery of said barrel, said pocket, in one position of said barrel relative to said main body, registering with said transverse opening and in another relative position registering with the small end of said funnel, said trunnions being formed with broad free ends engageable, respectively, by the thumb and a finger of one hand of an operator to hold said barrel against rotary movement while, with his other hand, the operator grasps said main body and turns the same about the axis of said barrel to vary the relative positions of said barrel and said main body whereby to shift said transverse opening and the small end of said funnel selectively into registry with said pocket.
